(57) **CLAIM**

The ornamental design for wearable novelty sign, as shown and described.

DESCRIPTION

FIG. 1 is a front elevational view of a wearable novelty sign;

FIG. 2 is a rear elevational view thereof;

FIG. 3 is a first front perspective view; and,

FIG. 4 is a second front perspective view.

The broken lines showing the head of a model wearing the wearable novelty sign are for illustration purposes only and form no part of the claimed invention.
